DES. 2171

Jasper Van Wormer of Albany N. Y.
Letters Patent No 2171 Dated Sept. 12, 1865
Design for a Wall Stove.

The schedule referred to in these Letters Patent and making part of the same.

Be it known that I Jasper Van Wormer of the City of Albany State of New York, have produced a new and original ornamental design for a Wall Stove; and I declare the accompanying (photograph) drawing, exhibiting in perspective, a stove, with all its plates in place, to be a full and complete delineation of the said Stove, with its ornamental figures.

That I claim as my production and desire to secure by Letters Patent, is the design for a Wall Stove as shown and described.
